CLAIM

The ornamental design for a vehicle body, as shown and described.

DESCRIPTION

FIG. 1 is a front perspective view of a vehicle body constructed in accordance with the teachings of the present invention.

FIG. 2 is a rear perspective view thereof.

FIG. 3 is a front view thereof; and,

FIG. 4 is a rear view thereof.

It will be understood that the left and right sides of the vehicle are substantially mirror images. It will be further understood that the broken line showing of wheels and tires throughout the drawings is for illustrative purposes only and forms no part of the subject invention.
